UNITED STATES PATENT OFFICE.

RUDOLPH C. SMITH AND WILLIAM SCHWANHÄUSSER, OF YONKERS, N. Y.

STOP-MOTION FOR ELEVATORS.

SPECIFICATION forming part of Letters Patent No. 307,814, dated November 11, 1884.

Application filed May 10, 1884. (No model.)

To all whom it may concern:

Be it known that we, RUDOLPH C. SMITH and WILLIAM SCHWANHÄUSSER, citizens of the United States, residing at Yonkers, in the 5 county of Westchester and State of New York, have invented certain new and useful Improvements in Stop-Motion for Elevators, of which the following is a specification.

The object of our invention is to prevent the 10 results ensuing in hoisting apparatus from the temporary arresting of the cage while the hoisting-rope continues its downward movement; and this object we effect through the medium of appliances, fully set forth hereinafter, which 15 arrest the driving mechanism upon the driving-rope becoming slack.

In the drawings, Figure 1 is an inverted plan of sufficient of a hoisting device to illustrate our improvement. Fig. 2 is a side view in 20 part section, and Fig. 3 is a section on the line 1 2, Fig. 1.

A B C are parallel shafts of the hoisting mechanism, the driving-shaft A carrying the idler-pulley b and the driving-pulleys a f, to 25 which the direct and cross bands D E are conducted, and upon which they are shifted by the movements of the shifting-bar F.

The shaft C carries the winding-drum G, driven from the shaft A through the intermediate shaft and its gears, as usual.

The cable x from the winding-drum passes over pulleys X to the cage or platform, which is raised or lowered, according as the drum revolves in one direction or the other.

An extension, e, on the shaft C is threaded 35 to receive a traveling nut, g, which travels between collars or shoulders s t upon the shaft, and slides in guide-grooves u in a shell or hollow drum, I, having upon the periphery an 40 annular rack, i, which engages with the teeth of a rack, J, upon a longitudinally-sliding bar, K. A second rack, L, upon the bar K gears with a pinion upon the shaft M, turning in 45 bearings upon the frame of the machine, and carrying a pinion, m, which engages with a rack upon the shifting-bar F. The shell I rotates upon bearings on a bracket, N.

As the drum G is turned in either direction, the nut g is prevented from turning by contact 50 with the shell I, but can travel freely in one direction or the other until it strikes the shoulder s or t, when the shell will be caused to re-

volve with the shaft, and the bar K will be moved longitudinally, sliding the bar F and shifting the belts as soon as the cage or platform reaches its upper or lower position. These features are well known and in common use; but we employ them, in connection with the devices which we will now describe, in order to shift the belts, whatever may be the position of the platform, should the hoisting-rope become slack. The opening in the shell I, through which the shaft C passes, permits the shaft to play independently of the shell, and the boxes P, instead of being permanently connected to their supporting-brackets Q, are arranged in slots therein, and rest upon spring-bearings p of such character that so long as there is any draft upon the hoisting-rope the shaft C will be central with the shell I; but 70 the bearings will yield under the weight of the shaft and its drum should the rope become slack.

The collar t is provided with teeth forming a ratchet-wheel, P', secured fixedly to the 75 shaft C, and the shell I carries within it a pawl, q, which, so long as the shaft and the shell are concentric, is free from contact with the ratchet-wheel, but when the ratchet moves downward or to one side, as results when the 80 shaft C sinks when the rope becomes slack, the pawl will engage with the ratchet. The contact of the ratchet and pawl results in causing the shell to revolve with the shaft and in moving the bars K and F, so as to shift the belts and 85 arrest the movement of the driving mechanism, the shifting of the belt being effected by the motive power of the machine.

A fixed pin may be substituted for the pawl q, and the shaft-bearings may be supported in 90 any suitable manner, so as to move in any direction as soon as the draft upon the hoisting-rope ceases, and any other belt-shifting appliances capable of being thrown into operation upon the shaft losing its alignment may be 95 employed, together with connections whereby the belt-shifting devices are positively operated by the motive power of the machine.

Without limiting ourselves to the precise construction and arrangement of parts described, we claim—

1. The combination, in a hoisting-machine, of a hoisting-drum carried by a shaft capable of a limited movement in or with its bearings

and driven by the motive power of the machine, a shifting device, and intermediate appliances, substantially as described, whereby such device is thrown into connection with the driving-shaft when the drum-shaft moves from the position in which it is maintained by the draft of the hoisting-rope, substantially as described.

2. The combination of the driving - drum having its shaft mounted in movable bearings and extending into a shell revolving upon fixed bearings, a belt-shifter, and projections upon the shaft and shell arranged to be brought in contact when the shaft moves from the position in which it is maintained by the draft upon the hoisting-rope, substantially as specified.

3. The combination of the hoisting - drum carried by the shaft turning in movable bearings having spring-seats, a ratchet, P', on the shaft, a shell, I, turning in fixed bearings and carrying a pawl, and a belt-shifter connected to be operated by the movement of the shell, substantially as described.

In testimony whereof we have signed our names to this specification in the presence of 25 two subscribing witnesses.

RUDOLPH C. SMITH.
WM. SCHWANHÄUSSER.
